DESIGN FOR A BLACK-OUT UNIT FOR TAILLIGHT LENS

Walter C. Thee, United States Army

Application February 2, 1942, Serial No. 105,600

Term of patent 3½ years

To all whom it may concern:

Be it known that I, Lieutenant Colonel Walter C. Thee, United States Army, a citizen of the United States, have invented a new, original, and ornamental Design for a Black-out Unit for Taillight Lens, of which the following is a specification, reference being had to the accompanying drawing, forming part thereof.

Fig. 1 is a front elevational view of a black-out unit for taillight lens showing my new design. Fig. 2 is a side elevational view thereof, and Fig. 3 is a rear elevational view thereof.

I claim:

The ornamental design for a black-out unit for taillight lens, as shown.

WALTER C. THEE.
